UNITED STATES PATENT OFFICE.

WALTER R. NATHANIEL, OF HOUSTON, TEXAS.

TRACK SWEEPING AND OILING DEVICE.

1,171,454.

Specification of Letters Patent. Patented Feb. 15, 1916.

Application filed August 6, 1912. Serial No. 713,644.

To all whom it may concern:

Be it known that I, WALTER R. NATHANIEL, a citizen of the United States, residing at Houston, in the county of Harris and State of Texas, have invented new and useful Improvements in Track Sweeping and Oiling Devices, of which the following is a specification.

This invention relates to a track sweeping and oiling device and the principal object of the invention is to provide an improved oiling device which is so constructed that it may be yieldably held in an inoperative position and moved into engagement with the track by means of a plunger when desired.

Another object of the invention is to provide a device of the character described which is so constructed that it will be strong and durable and not liable to easily get out of order or need repairing.

Another object of the invention is to so construct the device that it may be easily applied to cars now in use, no special car construction being necessary in order to mount the oiling device.

This invention is illustrated in the accompanying drawings, wherein—

Figure 1 is a side elevation of the device showing the same in conjunction with a platform of a car, Fig. 2 is a plan view of the device, Fig. 3 is a fragmentary sectional view of the device.

In the accompanying drawings the numeral 1 indicates the body portion or frame work of the device which body portion carries the discharge tube 6 adjacent one end. The upper end of this discharge spout 6 extends above the body portion as shown clearly in Fig. 3 to provide a sleeve 2 telescoping upon the lower end portion of the pipe 3. This pipe 3 passes through an opening formed in the platform *a* of a car and carries the oil tank 9, the outlet spout 10 fits into the upper end portion of the pipe 3 and is normally closed by a valve 13. This valve 13 is yieldably held in a closed position by the springs 15 and is provided with an operating stem 14 so that it may be moved to an inoperative position to permit oil to pass through the pipe 3 into the discharge spout 6. In order to yieldably support the body portion 1 and discharge spout 6 there has been provided springs 5 which are connected at their upper ends with ears 4 and have their lower ends connected with

the body portion and discharge spout. It will therefore be seen that the body portion and discharge spout may be normally held in a raised position but that they may be moved to an operative position when desired by means of the plunger 16, the plunger being connected with the body portion at 18 and provided with a handle 19.

The forward end portion 21 of the body portion is hingedly connected with the rear end portion for horizontal swinging movement and is yieldably held in a normal position by the springs 23 which are positioned between the forward end portion of the body portion and the free end portion of the yoke arms 20 extending from the rear end portion of the body portion. The free end portion of the rod 21 which forms the forward end portion of the body portion 1 is bent downwardly as shown at 30 and terminates in a plow 31 which fits into the depression of the rail indicated by the numeral 8 to remove hardened substances which may have gathered in the rail.

To the rear of the arm 30 which supports the plow there has been provided depending arms 25 which extend from the sleeves 24 and carry the springs 26 between which the handle or standard 28 of the brush is mounted. Therefore the brush will be yieldably mounted and can have free movement in a plurality of directions due to the action of the springs 23 and 26.

When this device is in use it is mounted as shown in Fig. 1 and oil is placed in the receptacle 9 through the inlet 11 which is then closed by means of the cap 12. As the car passes over the track the cleaning and oiling mechanism will be normally held in a raised position by the springs 5. When it is desired to bring the cleaning and oiling mechanism into use the plunger 16 is moved to force the body portion downwardly thus bringing the plow and broom into engagement with the rail and also bring the free end of the discharge spout into close engagement with the rail. The plow will remove stones and other articles from the groove of the track and will also loosen any dirt which may have collected in the groove. The broom will then sweep the track clear and the oil which passes into the discharge spout when the valve 13 is raised will drop upon the rail and lubricate the same. When the plunger is released the springs 5 will return the frame or body portion to its nor-

mal position where it will be held until again moved to an operative position by means of the plunger. Of course when the stem 14 of the valve is released the valve 5 will be moved into a closed position again by the springs 15 and thus further flow of oil out of the receptacle 9 will be prevented.

Having thus described the invention what is claimed is:—

- 10 1. A device of the character described comprising a body portion, an outlet spout having its upper end connected with said body portion, a tubular member slidably connected with the upper end portion of said 15 outlet spout, a receptacle carried by said tubular member, a spring connected with said body portion and with said tubular member, and a spring connected with said tubular member and with said outlet spout.
- 20 2. A device of the character described comprising a body portion, an outlet spout positioned beneath said body portion with its upper end connected with the same, a tubular member positioned above said 25 body portion with its lower end slidably con-

nected with the upper end portion of said outlet spout, a reservoir carried by said tubular member, a spring connected with said body portion and with said tubular member, a second spring connected with 30 said tubular member and with said outlet spout, and means for moving said body portion into and out of an operative position.

3. A device of the character described comprising a body portion, an outlet spout 35 connected with said body portion, a reservoir, a tubular member supporting said reservoir and connected with the upper end of said outlet spout whereby the contents of said reservoir may pass through said 40 tubular member into said outlet spout, resilient means connected with said body portion and tubular member, and resilient means connected with said outlet spout and tubular member.

WALTER R. NATHANIEL.
